DESIGN FOR A DISPENSING MACHINE

Stuart Burdette Burne, Brighton, N. Y., assignor
to Pulver Company, Inc., Rochester, N. Y., a
corporation of New York

Application December 23, 1944, Serial No. 117,046

Term of patent 14 years

(Cl. D52—2)

To the Commissioner of Patents:

Be it known that I, Stuart Burdette Burne, a citizen of the United States of America, residing at Brighton, in the county of Monroe and State of New York, have invented a new, original, and ornamental Design for a Dispensing Machine, of which the following is a specification, reference being had to the accompanying drawings, forming part thereof.

Fig. 1 is a front elevational view of a dispensing machine, showing my new design;

Fig. 2 is a side elevational view thereof; and

Fig. 3 is a perspective view thereof.

I claim:

The ornamental design for a dispensing machine, substantially as shown.

STUART BURDETTE BURNE.
